A. KAHLOW.
HINGE STRUCTURE FOR SUITCASES AND THE LIKE.
APPLICATION FILED SEPT. 25, 1919.

Patented Feb. 8, 1921.

UNITED STATES PATENT OFFICE.

ARTHUR KAHLOW, OF MILWAUKEE, WISCONSIN.

HINGE STRUCTURE FOR SUITCASES AND THE LIKE.

1,367,978.

Specification of Letters Patent.

Patented Feb. 8, 1921.

Application filed September 25, 1919. Serial No. 326,251.

To all whom it may concern:

Be it known that I, ARTHUR KAHLOW, a citizen of the United States, and resident of Milwaukee, in the county of Milwaukee and 5 State of Wisconsin, have invented certain new and useful Improvements in Hinge Structures for Suitcases and the like; and I do hereby declare that the following is a full, clear, and exact description thereof.

10 My invention relates to new and useful improvements in traveling bags, more particularly of that type wherein the sections of the suitcase or bag have their free edges secured to rectangular frames which are in 15 hinge connection to provide for opening and closing the receptacle, as shown in my previous Patent No. 860,806, granted to me July 23, 1907.

It is in general the object of my invention 20 to simplify and otherwise improve the structure, and to render more attractive the appearance of devices of this character.

It is more particularly my object to provide an arrangement wherein the body material of the suitcase is utilized to provide the hinge connection for the frames.

With the above and other objects and advantages in view, which will be apparent as the description proceeds, my invention relates 30 to the novel features of construction, combination and arrangement of parts as hereinafter described and claimed by the appended claims.

In the accompanying drawings:

35 Figure 1 is a perspective view of adjacent hinge corner portions of the frames of a suitcase or like receptacle embodying my invention.

Fig. 2 is a transverse sectional view 40 through the lower intermediate portion of the suitcase.

Referring more particularly to the accompanying drawings, it will be noted that as in my said previous patent, I provide a pair 45 of rectangular inner and outer metallic frames for bracing the free edges of the sections of the suitcase, the inner frame being adapted to nest within the outer frame and including a side rail channel portion 5 having a flange section 6 extending laterally therefrom for engagement within the corresponding flange portion 7 of the channel portion 8 of the outer frame side rail, the channel portions being adapted to receive

the body and lining of the suitcase sections 55 which are tucked and then clamped therein to provide an exceedingly attractive finish.

In my present improved structure, the lower ends of the side rail channel portions 5 of the inner frame are connected by a 60 simple channel rail 9 and the lower ends of the flanges 7 of the side section of the outer frame are connected by a flat metallic rail strip 10, substantially the width of said flanges. The bottom body boards or sheets 65 11 and 12 respectively of the two suitcase sections, together with their outer sheathings 13 and 14 respectively are tucked into the bottom channel section 9 and clamped therein by the usual rivets 15 passed through the 70 sides of said channel section. A common inner lining 16 is provided for the bottoms of the suitcase sections, said lining being extended about the channel section 9 of the inner frame and over the strap section 10 75 of the outer frame, being then continued over the body sheets 10 and 11 and upwardly at the sides of the suitcase. This lining is stitched to the body section at the side edges of the strip 9 as indicated by the 80 lines of stitching 17, there being only sufficient space between the strap 10 and the adjacent free side edge of the channel section 9 to permit this stitching. The lining is also stitched to the body sheet 11 at the 85 edge of the channel section 9.

An exceedingly simple, yet durable and effective hinge structure is thus provided, wherein the body material of the suitcase sections forms the hinge connection for said 90 sections and more particularly for the stiffening frames of the sections, it being noted that the hinge action of the body material is confined to a line A immediately adjacent the edge of the channel section 9 by reason 95 of the securement of the body sheet 12 and lining to the bottom strap section 10 of the outer frame. It is noted that the extreme hinge corner of the flange sections 7 of the outer frame form the terminals of the hinge 100 line A.

While I have shown and described a preferred embodiment of my invention, it will be appreciated that various changes and modifications of structure may be employed 105 to meet differing conditions of use and manufacture, without departing in any manner from the spirit of my invention.

What is claimed is:

1. A receptacle of the class described comprising a pair of sections, frames secured to the free edges of the sections, the sides 5 of each frame being formed with channels extending inwardly at right angles to the sides of the receptacle, the body material of both sections extending into the channel at one side of one of the sections and 10 clamped therein whereby to provide a hinge connection for the sections.
2. A receptacle of the class described comprising a pair of sections, inner and outer frame members secured to the free edges of 15 said sections, one rail of the inner frame section providing a channel member, the adjacent rail of the outer frame comprising a flat strip, the body material of one section being tucked into said channel, and the body 20 material of the other section being secured to said strip and then also tucked into said

channel of the other frame to provide a hinge connection for the sections.

3. A receptacle of the class described comprising a pair of sections, inner and outer 25 frame members secured to the free edges of said sections, one rail of the inner frame section providing a channel member, the adjacent rail of the outer frame comprising a flat strip, the body material of both sections 30 being tucked into said channel, a lining member disposed about the channel frame section and extended over the body material of the sections and stitching securing the lining to the body material of the adjacent section at the side edges of the strip frame portion.

In testimony that I claim the foregoing I have hereunto set my hand at Milwaukee, in the county of Milwaukee and State of Wisconsin.

ARTHUR KAHLOW.
